DESIGN FOR A BROILER GRILL

John F. Hennessy, Rockford, Ill., assignor to Geo.
D. Roper Corporation, Rockford, Ill., a corporation of Illinois

Application June 9, 1941, Serial No. 101,352

Term of patent 14 years

To all whom it may concern:

Be it known that I, John F. Hennessy, a citizen of the United States, residing at Rockford, in the county of Winnebago and State of Illinois, have invented a new, original, and ornamental Design for a Broiler Grill, of which the following is a specification, reference being had to the accompanying drawing forming part thereof.

In the drawing:

Fig. 1 is a plan view of a broiler grill showing my new design, and

Figs. 2 and 3 are longitudinal sections taken on the lines 2—2 and 3—3 of Fig. 1.

I claim:

The ornamental design for a broiler grill, substantially as shown.

JOHN F. HENNESSY.
